CLAIM

The ornamental design for a bicycle display, as shown and described.

DESCRIPTION

FIG. 1 is a front view of a bicycle display showing my new design;

FIG. 2 is a rear view thereof;

FIG. 3 is a left side view thereof;

FIG. 4 is right side view thereof;

FIG. 5 is a top view thereof;

FIG. 6 is a bottom view thereof;

FIG. 7 is a left, top, rear perspective thereof;

FIG. 8 is a right, bottom, rear perspective thereof;

FIG. 9 is a right, top, front perspective thereof;

FIG. 10 is a right, top, front perspective thereof showing the bicycle display attached to a bicycle; and,

FIG. 11 is a right, top, rear perspective thereof showing the bicycle display attached to the bicycle.

The broken line showing of the bicycle frame and wheels is for the purpose of illustrating a use on a bicycle and forms no part of the claimed design.
